CLAIM

The ornamental design for a mixer, substantially as shown and described.

DESCRIPTION

FIG. 1 is a perspective view of the mixer.

FIG. 2 is a top view of the mixer of FIG. 1.

FIG. 3 is a rear view of the mixer of FIG. 1.

FIG. 4 is a left side view of the mixer of FIG. 1.

FIG. 5 is a front view of the mixer of FIG. 1.

FIG. 6 is a right side view of the mixer of FIG. 1.

FIG. 7 is a right side view of the mixer in an alternate position.

FIG. 8 is a perspective view of the mixer in an alternate position; and,

FIG. 9 is a bottom view of the mixer.

Throughout the FIGS., broken lines are used to represent elements of the mixer which are not part of the claimed design.

1 Claim, 9 Drawing Sheets
